(57) **CLAIM**

The ornamental design for a dog car seat, as shown and described.

DESCRIPTION

FIG. 1 is a front, left and top perspective view of a dog car seat showing my new design;

FIG. 2 is a rear, right and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is a perspective view of the dog car seat, shown in condition of use.
The short dash-dash broken lines in all the figures illustrate portions of the dog car seat that form no part of the claimed design.

The long dash-dot broken lines in FIG. 9 showing the car interior and a dog, represent environmental subject matter that form no part of the claimed design.

1 Claim, 9 Drawing Sheets
